United States Patent Office.

CHARLES R. DOANE, OF BROOKLYN, E. D., NEW YORK.

Letters Patent No. 98,154, dated December 21, 1869.

IMPROVEMENT IN CARD-HOLDERS.

The Schedule referred to in these Letters Patent and making part of the same.

To all whom it may concern:

Be it known that I, CHARLES R. DOANE, of Brooklyn, E. D., in the county of Kings, and in the State of New York, have invented a new and useful Improvement in Card-Holders; and do hereby declare that the following is a full, clear, and exact description thereof, reference being had to the accompanying drawing, making a part of this specification, in which—

Figure 1 is a perspective view of my hanging card-holder, filled with cards;

Figure 2 is a like view of the same, with the cards removed; and

Figure 3 is a perspective view of a modification of the same; intended for use upon desks.

Letters of like name and kind refer to like parts in each of the figures.

In card-holders, as usually constructed, it is extremely difficult to remove one card, without partially or wholly removing others, and being required to replace the same.

To obviate this objection is the design of my invention, which consists in constructing the holder with its front and rear sides meeting at their bottom edges, and having relative angles of about thirty degrees, substantially as hereinafter specified.

In the annexed drawing—

A represents the back or vertical plate of the holder, having secured to its bottom edge the corresponding edge of the front plate B, which, from thence projects upward and outward at an angle of thirty degrees, or thereabout.

The holders intended to be suspended have the form shown in figs. 1 and 2, the back plate being extended upward, and provided with a suitable opening, a, at its upper end, to enable it to be passed over a nail or stud, while the lower part of said plate, and also the front plate, are divided by the removal of a piece of metal, corresponding in shape to the upper edge of the former. This form enables the holders to be cut without waste of metal.

In fig. 3, is shown a holder intended for use upon a desk, or other horizontal surface, in which the front and back plates correspond in height, the former be-

ing bifurcated, as in the hanging holder, and each half provided with a leg, b, cut therefrom, and bent forward, so as to prevent said holder from falling forward, while the rear plate is partially divided by means of two vertical slits extending upward from the lower edge, and the intervening metal C bent to the rear, so as to act as a leg or brace, by which means said holder is caused to remain steadily in the desired position with the rear plate vertical.

If, now, the cards D are placed upon some plane surface, and inclined to the front until their lower edges conform to the angle of the front plate, and then placed vertically within the holder, it will be found that the front card D' will fall forward against said front plate, as shown in fig. 1, in which position it may be readily grasped and removed.

As the front card is removed, the succeeding one immediately falls forward against the front plate, but in no case will more than one card fall at the same time, the others invariably retaining a vertical position.

The advantages possessed by this device, are as follows:

One card is always presented in such a manner as to permit it to be easily withdrawn without disturbing the others, which greatly adds to the convenience of the user, while, from its simplicity of form and ease of construction, the holder can be furnished at a very small cost.

Having thus fully set forth the nature and merits of my invention,

What I claim as new, and desire to secure by Letters Patent, is—

A card-holder, in which the front and rear sides meet at their lower edges, and from thence extend upward and apart at any suitable angle, substantially as and for the purpose specified.

In testimony that I claim the foregoing, I have hereunto set my hand, this 27th day of November, 1869.

CHAS. R. DOANE.
